H. I. AIKEN.
 ELECTRICALLY CONTROLLED CLOCK AND TIME INTERVAL TRANSMITTER.
 APPLICATION FILED DEC. 9, 1909. RENEWED DEC. 7, 1910.
996,551. Patented June 27, 1911.

996,551. ELECTRICALLY-CONTROLLED CLOCK AND TIME-INTERVAL TRANSMITTER. HAROLD ISAAC AIKEN, San Francisco, Cal. Filed Dec. 9, 1909, Serial No. 532,258. Renewed Dec. 7, 1910. Serial No. 996,171.

To all whom it may concern:

Be it known that I, HAROLD I. AIKEN, a citizen of the United States, and resident of San Francisco, in the county of San Francisco and State of California, have invented certain new and useful Improvements in Electrically-Controlled Clocks and Time-Interval Transmitters, of which the following is a specification.

My invention relates to the control of clocks or other time recording mechanisms, and it consists in the combinations, constructions and arrangements hereinafter described and claimed.

The invention is particularly applicable to time interval signaling, such as time interval systems for artillery fire control, or for other analogous uses employing instruments in which absolute chronometrical accuracy, irrespective of the size, or the weight of, or the load imposed upon the controlled mechanism, is essential.

A further object of my invention is to provide a controlling and transmitting device for use with instruments which are mechanically separate and distinct, and which may have any of a number of motive devices such as springs, suspended weights, electric motors, etc.

A further object of my invention is to provide a simple form of controlling and transmitting apparatus having few parts and therefore being less liable to get out of order.

My invention is illustrated in the accompanying drawings forming part of this specification, in which similar reference characters indicate like parts in the several views, and in which:

Figure 1 is a plan view of a portion of the controlling clock, provided with circuit closing devices, Fig. 2 is a side view of the circuit controlling device shown in Fig. 1, showing the connection of this device with the controlled instrument, Fig. 3 is a detail end view of a portion of the circuit closing device shown in Figs. 1 and 2, Fig. 4 is a plan view of a modified form of the circuit closing device, and Fig. 5 is a side view of the parts shown in Fig. 4.

In carrying out my invention I make use, for the controlling instrument, of an accurate clock 1, (preferably, but not necessarily, of the lever type). In the drawing, I have only shown a portion of this clock, since the operating mechanism therefor is not the subject of the present invention. Mounted upon the escapement 2 and oscillating there-

with is a light rocker arm 3. Each end of this rocker arm is provided with an inverted U-shaped platinum tip yoke, such as those shown at 4 and 5, which, at each down stroke, dips into the respective mercury cups 6 and 7. The mercury cups are carried on adjustable arms 6^a and 7^a on the standards 6^b and 7^b which are secured to the respective brackets 6^c and 7^c. The standards are insulated from each other and from the main clock by suitable insulation 8.

In Fig. 2 I have shown a portion of the controlled instrument. This, as stated above, is mechanically separate and distinct from the controlling clock and may be driven by any suitable source of power. The escapement wheel E' is similar to the escapement wheel E of the controlling clock. The escapement 9 of the controlled instrument is provided with a light bar 10 which is pivotally connected at its ends 10^a and 10^b with the respective bell-crank levers 11 and 12. The shorter ends of these levers are provided with armatures 11^a and 12^a, respectively, arranged to be operated by the magnets 13 and 14. The two standards 6^b are connected with the respective wires 15 and 16, the former leading to the magnet 13, and the latter to the battery B. The other end of the magnet coil is connected to the battery B by means of the conductor 17. The magnet 14 is similarly connected to one standard 7^b by the wire 18, and to the battery by the wire 19, while the wire 20 connects the battery to the other standard 7^b. The controlled clock is preferably provided with one or more impulse wheels 21 which are secured to the shaft 22 of the escapement wheel E'. These impulse wheels may be provided with any number of detents 23 arranged to engage the end 24^a of the bell-crank lever 24 which is pivoted at 25 and normally held in engagement with the impulse wheel by means of the adjustable contractile spring 26. When the end 24^a enters the detent 23, and the lever 24 engages the contact 27, the circuit is established from the battery B through the conductors 28, 24, contact 27, conductor 31, signal 32 and back to the battery by the conductor 33. The signal 32 may be a single stroke bell, and a number of these bells may be connected in multiple.

From the foregoing description of the various parts of the device, the operation thereof may be readily understood.

The oscillation of the rocker arm 3 with the escapement 2 causes the ends 4 and 5 to dip alternately into the mercury cups 6 and 7. When the end 4 is in the mercury cup 6, a circuit is established through the magnet 13, over the following path: battery B, 17, 13, 15, 6^b, 6, 4, 6, 6^a, 16, back to the battery. This energizes the magnet, the armature 11 is attracted, and the arm of the escapement is

rious parts of the device, the operation thereof may be readily understood. The oscillation of the rocker arm 3 with the escapement 2 causes the ends 4 and 5 to dip alternately into the mercury cups 6 and 7. When the end 4 is in the mercury cup 6, a circuit is established through the magnet 13, over the following path: battery B, 17, 13, 15, 6^b, 6, 4, 6, 6^b, 16, back to the battery. This energizes the magnet, the armature 11 is attracted, and the arm of the escapement is drawn down in the position shown in Fig. 2. When the end 5 of the rocker arm 3 is in the cup 7, the magnet 14 is energized, the circuit being from the battery B through 19, 14, 18, 7^b, 7, 5, 7, 7^b, 20 to the battery. The escapement 9 is then actuated, and the escapement wheel E' is turned the space of one tooth. As stated before, the impulse 20 wheels may have any number of detents. In the figure I have shown a wheel as being provided with four sets of detents arranged at 90°, there being three of these detents in each set. There will therefore be four sets 25 of three strokes each, of the bell 32 during one revolution of the escapement wheel E'. Of course, other arrangements might be made without departing from the spirit or the scope of the invention.

In order to prevent sparking at the mercury cups 6, I provide the condenser C which is shunted between the two standards 6^b. A similar condenser C' is in shunt between the standards 7^b. The condenser 30 and the 30 conductor 29 form the shunt circuit between the pivotal connection 25 of the lever 24 and the contact 27. This prevents excessive sparking at the end of the contact 27.

In Fig. 4, I have shown a modified form 40 of the circuit controlling device. In this form, the stiff spring terminals 34 and 35 have riveted to them the flexible springs such as that shown at 34^b. These flexible springs are provided with platinum contact

points such as 34^a, which project through 45 openings 34^b and are arranged to be engaged by the contacts 34 on each end of the rocker arm 3. The position of the contact points 34^a may be regulated by means of screws similar to that shown at 36. 50

The device described above, it will be seen, does not involve any mechanism which tends to retard the operation of either the controlling or the controlled clocks. The power for these clocks, as has been stated, may be entirely independent. 55

In the use of large instruments, such as tower clocks, or the swinging mechanisms of telescopes or other astronomical instruments, the actuating circuits of the magnets 60 13 and 14, or of the signals 32 may be relayed by local batteries, thereby insuring sufficient current for working these devices.

I claim:

The combination with the escapement of a 65 controlling clock, of a rocker arm secured thereto, and provided with contacts at each end, a pair of adjustable mercury cups secured to said controlling clock at each end of said rocker arm and adapted to receive 70 the respective contacts, a pair of magnets, circuit connections between each pair of mercury cups, and said magnets, a controlled clock provided with an escapement, pivotal connections from the armatures of 75 each of said magnets for operating the escapement of the controlled clock, an impulse sending wheel secured to the shaft of the controlled clock, a signal, a source of current, an electrical circuit comprising said 80 signal and said source of current adapted to be completed by a movement of the impulse sending device.

HAROLD ISAAC AIKEN.
